APPARATUS FOR HANDLING CONTACT
MASSES

Charles H. Lechthaler, Woodbury, and Russell Lee, Mantua, N. J., assignors to Socony-Vacuum Oil Company, Incorporated, a corporation of New York

Application April 15, 1943, Serial No. 483,120

4 Claims. (Cl. 23—288)

1

In the catalytic treatment of hydrocarbons, for such purposes as cracking high boiling hydrocarbons to gasolines, and for similar purposes, recently developed processes have made use of catalytic contact masses comprising formed particles or granules of alumina-silica complexes, and similar materials, such as fuller's earth, "Filtrol," and other natural clays, including altered and activated natural clays, synthetic composite particles arising from gels, and the like. These solid adsorptive catalytic materials are spoken of broadly under the term "clay type" contact mass materials.

In the first commercialization of catalytic cracking, the contact masses were composed of particle form clay type materials utilized as "beds-in-place" alternately subjected to reaction and to a combustion regeneration for the purpose of removing carbonaceous deposits placed upon the contact mass during reaction to revivify it for further reaction.

More recently processes have been developed wherein the contact mass particles are moved cyclically, first through a zone wherein the desired hydrocarbon reaction is conducted and the contact mass contaminated by carbonaceous deposits laid down thereon, and second through a zone wherein these deposits are removed by burning, after which the contact mass particles return to the first named zone. When the contact mass particles are of appreciable size such as pellets or granules of about 30 mesh per inch size or larger, there is a certain production of fines, as by attrition, etc. With such processes employing particles of appreciable size, the contact of reagent and contact mass, or of regeneration agent and contact mass is achieved by flowing the fluid reagents or regenerant through the interstices in the moving bed of contact mass. Fines of contact mass material give rise to trouble when present in excess amounts.

This invention has for its object the removal of fines of contact mass material from processes wherein a particle-form solid contact mass material having appreciable particle sizes, say above about 30 mesh, is cyclically moved through a reaction zone where hydrocarbon reaction is conducted, thence through a regenerating zone, and then returned to reaction.

Separation of fine particles from coarse particles of solid may be conducted in several different ways, as by screening, use of centrifugal force, electrical precipitations, or elutriation. In the surroundings spoken of the application of any screening method is open to many mechan-

2

ical difficulties because of high temperatures, presence of corrosive materials and other difficulties. Cyclone separators are not found highly useful for other than very rough separation. 5 Electrical precipitation, suitable for removing extremely small particles when present in small concentration, is not applicable to what is really a problem of size separation. This invention has applied, in a specific manner, the process of elutriation, that is, contact of a particle stream with countercurrently flowing gases at rates designed to remove all particles smaller than a desired size.

In order to conveniently understand the invention, reference is now made to the drawings attached hereto. In these drawings, Figure 1 serves to show, diagrammatically, the surroundings in which the invention is practised. Figure 2 shows in diagram form a vertical section of apparatus appropriate for its practise, Figure 3 shows a plan view of the apparatus of Figure 2, Figures 4 and 5 show a detail therein, and Figures 6 and 7 show an optional form for that detail.

In Figure 1, item 10 is a reactor through which 15 a stream of contact mass particles passes in a downward direction to be contacted with hydrocarbon reactants introduced by pipe 11 and removed by pipe 12. Spent contact mass material 20 passes from the reactor through duct 13 and is elevated by elevator 14 to pass through duct 15 into the upper end of a regenerating kiln 16. In this regenerating kiln 16 regeneration medium, usually air, is fed by pipe 17 through orifices 18 into each of several stages within the kiln wherein 25 regeneration is completed. Leaving kiln 16 by ducts 19 from each stage, the flue gases are collected into each of two ducts 20 and pass upwardly. Above kiln 16 there is a fines cleaning 30 device composed substantially of a vertical member 21, which is described later in more detail. By means of ducts 22 and dampers 23, a portion of the flue gas is forced to flow into cleaning column 21, the remainder passing upwardly to 35 enter a final separator 24 by means of ducts 25. Flue gases from cleaning column 21 pass through ducts 26 into ducts 20 to similarly enter separator 24. These flue gases from 21 contain the fines cleaned from the contact mass material. 40 All fines separated in 24 are discharged from the system through pipe 27, clean flue gases being discharged to atmosphere through pipe 28. The regenerated contact mass material flowing from the bottom of kiln 16 through duct 29 is 45 elevated by elevator 30 and discharged through 50 55

duct 31 into a storage hopper 32 from whence it flows by duct 33 into reactor 10. A portion of this regenerated material is conducted by duct 34 to cleaning column 21. The portion selected for cleaning may be taken either from the regenerated material, as shown, or from the spent material flowing through duct 15. In general, it is preferred to work with regenerated material for various reasons, such as for example, it is easier to handle in cleaning, and this choice is usually reenforced by not having to build the spent catalyst elevator 14 sufficiently great in height to give access to the top of cleaning column 21.

Turning now to Figure 2, we have a detail showing the top of the regenerator kiln 16 into which contact mass material has been fed by duct 15 and from which there extends upwardly the cleaning column 21. A portion of the contact mass material is fed through duct 34 to the top of 21, the amount so fed being controlled by a sliding orifice plate or other appropriate type of valve 35. Inwardly of column 21, duct 34 terminates in a feed pipe 36 below which there is positioned a distributing cone 37 so that the contact mass particles are distributed uniformly in a shower in the interior of cleaning column 21. Cleaned material from the bottom of 21 passes through pipe 38 into the interior of kiln 16, this pipe terminating in a cone 39 at a point below the level of contact mass material in the kiln as designated by line 40. Flue gas from kiln 16 is introduced into cleaning column 21 by means of ducts 22 which lead into a pressure chamber 41 surrounding the cleaning column near its bottom, the wall of the column being perforated by orifices 42 so that a uniform and proper distribution of gas into the cleaning column 21 may be effected. Outgoing gases laden with fines leave cleaning column 21 through ducts 26 and pass into ducts 25 and thence into separator 24. In separator 24 the fines are thrown out, departing from the system at 27, with clean flue gas departing at 28.

Figure 3 is a plan view of the apparatus shown in Figure 2, serving merely to indicate its general arrangement. In this figure, 16 is the regenerator, 15 the feed duct therefor, 21 is the cleaning column, 34 is the pipe feeding solids thereto, 35 the valve in that feed pipe, 41 the inlet gas pressure chamber, 22 and 22 the inlet gas feed ducts, 26 and 26 the outlet gas ducts, 24 the separator, 25 and 25 ducts leading flue gas thereinto and 28 the stack of the separator.

In Figures 4 and 5, which should be read together, we find a detail of the arrangements for introducing contact mass material in a uniform manner to the cleaning column 21. In the column 21 the feed pipe 36 is centrally located extending therein to a depth indicated by line A, sufficient to permit a reasonable collection space for discharged gases above the point of contact mass introduction. Just below the end of pipe 36 there is mounted distributor cone 37 which, by experiment, has been found to be preferably a cone having 45° sides and a base diameter about one-third the diameter of the cleaning column 21, so mounted that its apex is practically at the level A. (The slope of the cone will depend somewhat upon the nature of the solid material being handled.) Additionally, this cone is provided with certain orifices 43, the number and size of these orifices being so selected that a portion of the contact mass material flowing over the surface of the cone is discharged therethrough to provide about the same mass velocity of con-

tact mass in the area below the cone as in the area fed by spillage over its edges.

In Figures 6 and 7, there is shown a manner in which this detail of design may be handled in a cleaning column of considerably larger dimension wherein, in a column 21 fed by a pipe 36, that pipe is divided into several pipes 44, each with its own cone 45, these pipes and cones being so arranged as to secure a substantially uniform distribution over the entire area of cleaning column 21.

In this cleaning column, the method of cleaning is by conducting a falling shower of contact mass particles including fines with an upwardly ascending column of gases of predetermined velocity sufficient to sweep from that column of particles all particles finer than a certain predetermined size.

In application to the present operation in which this method of cleaning is applied, wherein we are circulating a stream of contact mass particles continuously through two zones, in one of which they are contaminated by reaction and in the other of which they are regenerated by combustion, we segregate a relatively quite small portion of the circulating stream of contact mass material, scrub it with a portion of the flue gases from regeneration, return the scrubbed stream of contact mass material to cycle and discharge the flue gases, after separating and discarding fines therefrom, to the atmosphere.

There are two fundamental controls for this operation. The first is that of gas velocity in the upwardly ascending stream of gas. This is so adjusted as to be maintained slightly above the "terminal velocity" for the largest particle to be eliminated. Terminal velocity may be defined as that velocity of gas which will prevent the falling of a selected particle.

For catalyst particles ranging in size from 14 to 60 mesh (Tyler scale) in flue gas at 800°-1100° F. and atmospheric pressure, terminal velocity is expressed by the Allen-Glazebrook equation as:

$$V = 0.605k \cdot \frac{o-p}{p} \cdot g \cdot \frac{a-h\bar{a}}{v}$$

Where:

V = terminal velocity in cm./sec.,

$\bar{a}$ = the critical radius of the particle above which Stoke's Law is not obeyed,

$$\bar{a}^3 = \frac{9}{2} \frac{v^2}{g} \left(\frac{o-p}{p} \right)$$

o = density of the particle in gm./cc.,

p = density of the fluid in which the body falls in gm./cc.

g = acceleration due to gravity, 981 cm./sec.²

a = radius of the particle in cm.,

v = kinematic viscosity of the fluid, $\frac{u}{p}$, in Stokes, where

u = absolute viscosity of the fluid in poises

k and h = constants depending upon the shape particle. For catalyst granules $k=0.31$, $h=-1.1$

A discussion of this formula may be found in Geoffrey Martin, A Treatise on Chemical Engineering; Crosby Lockwood and Son, London, pp. 30.1-30.12, 1928.

Reduced to concrete terms in an example, to remove particles of 35 mesh and finer having a specific gravity of 1.45, when the fluid supporting medium is flue gas at 900° F. and atmospheric pressure, the velocity should be 8.2 feet per second. With this velocity, the separated catalyst fines will be found to be of all sizes up to and in-

cluding 35 mesh, the bulk of them being below that size.

The other control is the proportionate amount of contact mass subjected to cleaning. The degree of removal of fines from the total amount circulating may be increased or decreased by increasing or decreasing the proportion subjected to cleaning. Greatest efficiencies of removal are obtained when the amount of material subjected to cleaning does not exceed 1 ton/hr. per sq. ft. of cleaning column cross sectional area. The actual amount so subjected is found to be quite small. For example, in a unit circulating 100 tons per hour, only 5 tons per hour need be subjected to cleaning in order to have the whole substantially free of fines, when the contact mass particles have the resistance to attrition ordinarily characteristic of pelleted clays. This figure will vary, of course, with the resistance of the contact mass to attrition, since less resistant particles will give rise to more fines and will require that a greater proportion be subjected to cleaning to secure equal freedom from fine particles.

We claim:

1. In a system for the conversion of hydrocarbons in the presence of a particle form solid contact mass material a reaction zone, means to introduce particle form solid contact mass material thereto and means to remove it therefrom, means to introduce hydrocarbon reactants thereto and means to remove hydrocarbon reaction products therefrom, a regeneration zone, means to introduce contact mass material thereto and means to remove it therefrom, means to introduce fluid regenerating medium thereto and means to remove it therefrom, means to transfer spent contact mass from the reactor to the regenerator, means to transfer regenerated contact mass from the regenerator to the reactor, means to divert a portion of the moving stream of contact mass at a point between the regenerator and the reactor, scrubbing means for said diverted contact mass comprising a vertical passage, means to introduce diverted contact mass to said passage to pass downwardly therethrough as a shower, means to flow a gas upwardly through said passage at controlled velocity sufficient to remove finer particles of contact mass from said shower, separate exit means from said passage for fines-laden gas and for cleaned contact mass, and means to return said cleaned contact mass to the cycle and means to discard said removed fines from the system.

2. In a system for the conversion of hydrocarbons in the presence of a particle form solid contact mass material a reaction zone, means to introduce particle form solid contact mass material thereto and means to remove it therefrom, means to introduce hydrocarbon reactants thereto and means to remove hydrocarbon reaction products therefrom, a regeneration zone, means to introduce contact mass material thereto and means to remove it therefrom, means to introduce fluid regenerating medium thereto and means to remove it therefrom, means to transfer spent contact mass from the reactor to the regenerator, means to transfer regenerated contact mass from the regenerator to the reactor, means for cleaning less than all of the moving stream of contact mass from fines comprising a confined vertical passage, means to admit a controlled portion of the moving stream of contact mass thereto from a point between the reactor and the regenerator, means to distribute the contact mass so admitted into a shower falling substantially uniformly through all of the horizontal

cross section of such passage, means near the bottom of such passage to admit a gas substantially uniformly to all portions of the cross section of such passage, means to control the amount of gas so admitted to give a gas velocity countercurrent to said shower sufficiently great to float and remove therefrom particles of less size than a selected minimum size, exit means for fines-laden gas near the top of said passage, and means for returning only the cleaned contact mass material to the cycle.

3. In a system for the conversion of hydrocarbons in the presence of a particle form solid contact mass material a reaction zone, means to introduce particle form solid contact mass material thereto and means to remove it therefrom, means to introduce hydrocarbon reactants thereto and means to remove hydrocarbon reaction products therefrom, a regeneration zone, means to introduce contact mass material thereto and means to remove it therefrom, means to introduce fluid regenerating medium thereto and means to remove it therefrom, means to introduce fluid regenerating medium thereto and means to remove it therefrom, means to transfer spent contact mass from the reactor to the regenerator, means to transfer regenerated contact mass from the regenerator to the reactor, means for cleaning less than all of the moving stream of contact mass from fines comprising a confined vertical passage, means to admit a controlled minor portion of the moving stream of contact mass thereto from a point between the reactor and the regenerator, means to distribute the contact mass so admitted into a shower falling substantially uniformly through all of the horizontal cross section of such passage, means to admit gas to flow upwardly through said passage at rates substantially uniform across the cross section thereof, means to control the amount of gas so admitted to give a gas velocity countercurrent to said shower sufficiently great to float and remove therefrom particles of less size than a selected minimum size, exit means for fines-laden gas near the top of said passage, a gas-solid separator for removing fines from said fines-laden gas, means to direct said fines-laden gas from said exit means to said separator, a gas outlet from said separator, an outlet for withdrawal of said fines from said separator to a location outside of said system and means for returning cleaned contact mass material to the cycle.

4. In a system for the conversion of hydrocarbons in the presence of a particle form solid contact mass material a reaction zone, means to introduce particle form solid contact mass material thereto and means to remove it therefrom, means to introduce hydrocarbon reactants thereto and means to remove hydrocarbon reaction products therefrom, a regeneration zone, means to introduce contact mass material thereto and means to remove it therefrom, means to transfer regenerated contact mass from the regenerator to the reactor, means to divert a portion of the moving stream of contact mass at a point between the regenerator and the reactor, scrubbing means for said diverted contact mass comprising a vertical passage, means to introduce diverted contact mass to said passage to pass downwardly therethrough as a shower, means to flow a gas upwardly through said passage at controlled velocity sufficient to remove finer particles of contact mass from said shower, means to divert a portion of the regenerator ef-

fluent gas to provide gas to be used in said scrubbing means, separate exit means from said passage for withdrawal of fines-laden gas from said system and for cleaned contact mass, and means to return only said cleaned contact mass to the cycle.
